RAZOR

Jacob L. Kleinman, Bronx, N. Y.

Application July 31, 1935, Serial No. 33,973

20 Claims. (Cl. 30—65)

This invention relates to razors, blade holders and razor blades, and more particularly to razors and blades of the safety type, and is an improvement of applicant's invention patented July 19, 5 1932, No. 1,868,239.

A primary object of this invention is to provide a blade with a non-flexible center portion, so that the flexing strain is borne by the side sections of the blade, thus holding firmly the cutting edges 10 of the blade, thereby controlling the fineness of the cut or shave.

Another object of this invention is to provide a blade so constructed that same may be flexed in either direction thus possessing superior strength 15 and resilience.

A further object is to provide a blade having an opening or slot at about the center portion thereof, thus dividing the blade into two side sections held together by bridge portions of a re-enforced 20 nature, thus minimizing breakage possibilities of same.

A still further object of this invention is to provide a blade having an opening or slot at about its center portion, thereby dividing the blade into 25 two side sections held together by bridge portions, the inner end portions of said sections and the bridge portions being of a heavier thickness than the rest of the side sections, so that when the side sections are being flexed, the inner sections may 30 remain firm, thus eliminating vibration of the cutting edges.

Yet another object of this invention is to provide a blade having its center portion of a heavier thickness than the side sections of same, so that 35 the flexing strain is borne by the side sections, and, in addition thereto, said heavier portion is also forming the guiding means for positioning said blade in its proper position when being placed within a holder for shaving purposes.

A still further object is to provide a blade so constructed that the flexing strain is borne mainly by the side sections, thereby obtaining a firm and steady cutting edge of the blade.

Yet a further object is to provide a safety razor 45 wherein although the handle, plate and cover are secured to each other in a manner so as to provide a one-piece holder, yet the flexing of the blade may be controlled and the edges thereof move freely and be tilted.

A still further object of this invention is to provide a razor wherein although the handle and associated parts are secured to each other, yet the blade may move freely therein and be readily 50 adjusted, and the edges thereof may move freely

and be tilted to any angle desired, thus varying the fineness of the cut or shave.

Yet another object of this invention is to provide a razor wherein the holder and blade are each provided with gauge portions so that the 5 positioning of the blade within the holder may thus be controlled.

A still further object is to provide a blade holder consisting of a unit including means for receiving a blade, and a member provided with 10 suitable means for engaging and flexing the blade, so as to adjust the cutting edges to any desired position without affecting or separating the portions of the holder.

All of the above objects will be seen to be directed towards providing a practical shaving device, a blade that is useful and durable, simple in construction, economical in cost of manufacture, adaptable for use with various types of holders, therefore practical and economical for the 15 consumer.

Other objects and advantages of the present invention will appear from the description thereof to follow, taken in connection with the accompanying drawing, in which—

Fig. 1 is an assembled view of the razor and 25 blade, embodying my present invention;

Fig. 2 is a perspective view of the upper portion of the blade holder;

Fig. 3 is a plan view of a modified guard plate 30 upon which the blade is adapted to rest;

Fig. 4 is a perspective view of a portion of the blade carrier;

Fig. 5 is a modification of Fig. 1, the handle 35 partly broken away;

Fig. 6 is a perspective view of the blade;

Fig. 7 is a modified form of Fig. 6;

Fig. 8 is an end view of Fig. 6 showing how the flexing strain is borne by the side sections of the blade and,

Fig. 9 is a transverse cross-section at right angles to Fig. 1 on line 9—9.

Referring to the drawing; (Figs. 1, 2, 3 and 9) 45 5 indicates a handle secured to opening 6 of plate 7, said plate 7 is provided with a depressed portion or recess 8, said recess is provided with a groove or channel portion 9, a movable member or carrier 10 is positioned within said groove 9, said carrier is provided with an extension 11 positioned within slot 12 of plate 7. The upper portion of the handle 5 is also slotted in a manner to correspond with the slot 12 to an extent sufficient to 50 permit the downward movement of the carrier 10. The center portion 14 of carrier 10 is positioned within the hollow of the handle 5 and is provided 55

with a screw threaded section. The open end portion of the handle 5 is covered with a knob or cover 16. The end portion of wall 17 of said cover is bent, wedged or pressed into a groove of the handle 5 as at 18, thus securing the cover to said handle and permitting the rotation of said cover. The cover 16 is provided with a screw threaded section 19, engaging the screw threaded section of portion 14, so that upon the rotation of the 10 knob or cover 16, the portion 14 and carrier 10 will move longitudinally of the handle 5.

A cover plate 21 is suitably secured to plate 7, for example, by means of lugs 22, which may be bent, wedged or squeezed as at 23, leaving a space 15 or front opening 24, (by means of lugs 25 or any other suitable means) so that a blade may be inserted therein. The rear end section of said space or opening is provided with an extension, lug or bent portion 26 which acts as a stop or gauge for 20 the blade to hold same in position within said opening 28, so that when the holder is held with the opening 28 upward, a blade may be safely inserted therein, whereas a turn of the holder bringing opening 28 downward, will bring the blade 25 from its position for removal from the holder.

The modified form illustrated in Fig. 5, shows the handle 5' (partly broken away) secured to a plate 7' to which a cover 21' is hingeably connected by suitable hinging means, for example, 30 as at 31. A suitable locking device comprising, for example, a spring 32 is arranged thereto, so that cover 21' may be opened or closed for the purpose of placing or removing a blade. The locking member 32 is secured to the cover so that 35 when the holder is closed, said locking member engages the plate at 33, thus holding said cover and the blade in position.

With particular reference to Figs. 6, 7 and 8, the kind of safety razor blades used at present for 40 shaving, for example, the kind known as Probak, Gillette, Segal or other similar types, are usually made of a uniform thickness throughout the full size (length and width of blade). Therefore, when the blade is being flexed while tightening the holder, the center portion of the blade is subjected to the major flexing strain caused by such flexing, resulting in an occasional snapping or breakage of the blade at such center portion; particularly is that true with the type of blades where the center 45 portion is punched out forming a longitudinal slot leaving two side sections and two bridge portions or end sections holding such side sections together. Such bridge portions are much too weak to bear the strain caused by the flexing of the blade. Furthermore, because of the longitudinal slot in such blades, the center portions of the side sections are without the necessary support. Thus, while shaving, the cutting edge vibrates and 50 jumps, cutting the hairs not at their base but away from the skin, so that a "pull" effect is felt. This, of course, is very much objectionable and in many instances makes the blade useless for proper shaving purposes, causing irritation and sometimes leaving a "marked" face to the one desiring a 55 "clean" and "smooth" shave. Because of such experience, applicant, whose record will prove that he has been engaged in research work for many years, has spent quite some time in extensive and costly experiments and research work 60 until he has finally invented a blade that, although a slot may be formed therein, yet the removal of the material by forming such slot will not affect the side sections, therefore eliminating vibration of the cutting edge while shaving; nor 65 will it cause the bridge sections to snap or break.

Not only that, but furthermore, according to applicant's present invention, the bridge sections are being re-enforced so that ordinary snap or breakage by reason of flexing the blade while tightening the holder, is being entirely eliminated.

The blade herein referred to is illustrated by numeral 35 and is of the usual thickness, but the novel feature of applicant's invention, (which applicant is hereby desirous of pointing out) consists of the fact that the strip (from which the blade 35 is made) is provided with a slightly heavier center section longitudinally thereof so that the center portion 36 of blade 35 is of a heavier gauge or thickness than the side sections 39, thus increasing the strength and life of the 10 blade considerably. A slot 37 may be formed within such heavier center portion so that the edge 38 of said slot 37 may be held rigidly in its place. In fact, the entire center section A, because of its heavier thickness in comparison with 15 that of the side sections 39 will not flex cross-sectionally to an effective extent, but the flexing strain will be overthrown to and borne by the side sections 39 as at B (see Fig. 8).

Of course, it is immaterial whether the edge 38 25 is of straight or fancy cut, as long as it is within and a portion of the heavier center section. The side sections 39 will, in such a case, be apt to flex more readily and easier than the center section. Of course, the thickness may be decided upon 30 when making the strip of steel from which the blade is made. After all, the thickness of the center portion is not so very much greater or heavier than that of the side sections and although because of its narrower width such heavier 35 center portion will not flex cross-sectionally to such an extent as will the side sections, yet, when in a long strip, it will flex longitudinally to an extent sufficient to be rolled into a coil, so that the blade chopped off from such strip or coil will 40 not be brittle and may, notwithstanding the strain of the heavier center portion, be flexed in either direction thereby minimizing breakage possibilities (which is a common occurrence with blades of the ordinary type). Thus applicant's present 45 invention is solving the problem of the safety razor blade in a practical manner. The blade 35 is at its center portion provided with a bead, extension or projection 41. The movable member or carrier 10 is provided with a groove 42, adapted 50 to receive the projection 41 so that when shaving is desired, knob or cover 16 is rotated until carrier 10 is brought into its position flush or even with the surface of the recess 8. Then the blade is inserted as aforesaid; the center portion 36 fits 55 within said recess 8 (so that in addition to its important function as above explained, it also acts as a guide, so that the blade may be properly positioned within the holder). The projection 41 will then find itself positioned within the groove 60 42 of carrier 10, so that when the knob 16 will be rotated in the proper direction; the carrier 10 will move upward carrying or pressing the center portion 36. The end sections 44 will be held against the end portions 45 of cover plate 21. Thus 65 the sections 39 will flex and because of the radius of the comb or teeth section 46, and, because of the space between edge 45 and comb portion 46, the edge portions 44 will move freely and tilt until the desired angle is obtained. Of course, by turning the knob in either direction, such tilting may be controlled and adjusted to suit the individual's 70 tenderness of the skin or roughness of the beard. Thus a practical shaving instrument is obtained. It is understood that various changes in the 75

structure or in the hinging or locking arrangements may be resorted to.

If desired, the connection between the carrier and knob may be re-arranged; for example, the 5 knob may be provided with an extension engaging directly the body of the carrier, in a screw threaded connection; or the handle, instead of being permanently secured to the plate 7, may be detachably secured thereto so that it may be taken 10 apart whenever desired.

It will be seen from Fig. 3 that the recess 8 may be eliminated, and that bead or extension 41 of the blade 35 and groove 42 of the carrier 10 may be the sufficient means for guiding and holding 15 the blade when positioned within the holder for shaving purposes. In such a case the thickness of the end section of the re-enforced center portion 36 may be gradually reduced until it will meet the thickness of the side sections 39, so that the 20 end edges of portion 36 will not be visible. Of course, for that matter, if desired, the beads 41 may be eliminated, especially when an opening is made in the blade with a view of using it in connection with the present type holders. It 25 really does not matter how the re-enforced center portion is made, so long as it answers the purpose of overthrowing the flexing strain upon the side sections 39, and minimizes the flexing possibilities of the center portion, thereby preventing breakage of such center portion or center sections, or 30 may eliminate vibration of the cutting edge. Then and in such case, such structure will be or rather is within the spirit of this invention. As a matter of fact, applicant realizes and is aware of 35 the fact that various changes may be resorted to in the course of manufacturing with the object in view of producing a blade which may answer the purpose of applicant's invention. Of course, such a blade would naturally be within the spirit 40 of applicant's present invention.

Applicant has shown certain preferred forms in order to explain and show the novelty of his invention; but by showing such preferred structure I do not, by any means, limit myself to this structure, nor to the terms used in describing same. Various suggestions and changes of structure or 45 terms may be resorted to, and I desire it to be understood that I have same in mind when describing this invention, and seek protection by 50 Letters Patent, and although I have mentioned in describing of what materials certain parts may be made, how they may be shaped or styled and how they may be assembled, yet I desire it to be understood that this structure or parts thereof 55 may be made of any suitable material and in any desirable style or shape and assembled in any suitable manner, and that various changes in detail may be resorted to without departing from the spirit of this invention.

60 I claim:

1. A one-piece razor holder comprising a handle, a plate and a cover, said plate provided with a recess adapted to receive a portion of a blade, thus holding same against angular displacement, 65 said recess provided with a groove, a movable member for engaging said blade positioned in said groove, and rotatable means associated with said holder adapted to exert a pressure against a portion of said member, moving same longitudinally of said handle, thus flexing said blade and tilting the edges of same.

2. A device forming a razor blade holder comprising a handle and a top-unit, said top-unit including upper and lower sections, said lower 75 section being provided with a recess, a movable

bar seated within said recess, at least a portion of the upper section of said bar being grooved, a blade positioned within said top-unit, said blade provided with a projection adapted to interfit with the groove of said bar thus being held against 5 angular displacement.

3. A device forming a razor blade holder comprising a handle and a top-unit, said top-unit including upper and lower sections, said lower section being provided with a depressed portion, 10 a movable bar adapted to rest within said depressed portion, said bar provided with a recess, a flexible blade positioned within said top-unit, said blade provided with a projection, the recessed portion of said bar adapted to engage said projection thus holding said blade against angular displacement, said handle being provided with rotatable means co-operating with a portion of 15 said bar for moving same longitudinally of said handle thus flexing said blade thereby tilting the 20 edges of same.

4. A device forming a razor blade holder including a handle and a top-unit, said top-unit including upper and lower sections, said sections being so arranged as to provide means for supporting a blade therebetween, a movable member associated with said top-unit, said lower section provided with means forming a seat for at least a portion of said member, the upper section of said member provided with a cut-out portion 30 adapted to interfit with a portion of said blade thus holding the latter against angular displacement, means within said device for moving said member longitudinally of said handle and adjusting said blade for shaving purposes. 35

5. A razor blade holder comprising a handle and a top-unit, said top-unit provided with means adapted to support a blade, the portion of said top-unit below said blade provided with a recess, a movable member positioned within said recess, 40 rotatable means associated with said holder for moving said member longitudinally of said handle, said member provided with a grooved portion adapted to receive a portion of said blade thus holding same against angular displacement and 45 also to flex same thereby tilting the edges thereof.

6. A device forming a razor blade holder including a handle and a top-unit, said top-unit including upper and lower sections, said sections provided with means for receiving a blade there- 50 between, a bar located between said sections, a portion of said bar being movably positioned within an opening in said lower section, said bar provided with a grooved portion adapted to support a portion of said blade and means associated 55 with said device for moving said bar longitudinally of said handle thus adjusting said blade for shaving purposes.

7. A holder for razor blades comprising a han- 60 dle and a top-unit, said top-unit including upper and lower sections hingably securely to each other, said lower section provided with a recess, a movable member positioned within said recess, said member provided with a grooved section adapted to engage a portion of a blade supported 65 by said top-unit, said holder provided with means for moving said member longitudinally of said handle thereby flexing said blade so that a rigid cutting edge for shaving purposes may thus be provided. 70

8. A holder for razor blades comprising a han- 75 dle and a top-unit, said top-unit including upper and lower sections, said sections provided with means adapted to receive a blade there- between, a bar located between said sections, said

- bar provided with a grooved portion adapted to support a portion of said blade, and means associated with said handle adapted to move said bar longitudinally of said handle.

5. 9. As a new article of manufacture, an integral razor blade made of a strip of spring steel and comprising longitudinal flexible side sections and a relatively thicker longitudinal center portion of a heavier gauge than that of the side sections, the longitudinal end portions of said side sections being of such a thickness as to permit the flexing of said end portions in either direction, transversely or longitudinally, at least one of said longitudinal end portions being provided 10 with a sharpened edge, said center portion being of such thickness that it is flexible longitudinally of the blade but is substantially non-flexible transversely of the blade, whereby flexing strain cross-sectionally of the blade is borne substantially entirely by said side sections of the blade.

15. 10. A blade according to the structure as set forth in claim 9, wherein the longitudinal center portion is provided with an aperture, thereby dividing the blade into two sections held together by reinforced bridge portions.

20. 11. As a new article of manufacture, an integral razor blade made of a strip of spring steel and comprising longitudinal side sections and a relatively thicker longitudinal center portion of a heavier gauge than that of the side sections, said side sections being of approximately uniform thickness throughout and flexible in either direction, transversely or longitudinally, at least one of said side sections being provided with a 25 sharpened edge, said center portion being of such thickness that it is flexible longitudinally of the blade but is substantially non-flexible transversely of the blade, whereby flexing strain cross-sectionally of the blade is borne substantially entirely by said side sections of the blade.

30. 12. A blade according to the structure as set forth in claim 11, wherein the longitudinal center portion is provided with an aperture, thereby dividing the blade into two sections held together 35 by reinforced bridge portions.

35. 13. As a new article of manufacture, an integral razor blade made of a strip of spring steel and comprising a longitudinal flexible side section and a relatively thicker longitudinal portion 40 of a gauge heavier than that of the side section, the longitudinal end portion of said side section being of such a thickness as to permit the flexing of same in either direction, transversely or longitudinally, said end portion being provided 45 with a sharpened edge, said thicker portion being of such a gauge that it is flexible longitudinally of the blade but is non-flexible or substantially so transversely of the blade, whereby flexing strain cross-sectionally of the blade is borne substantially entirely by said side section.

50. 14. As a new article of manufacture, an integral razor blade made of a strip of spring steel and comprising longitudinal flexible side sections and a relatively thicker longitudinal center portion 55 of a heavier gauge than that of the side sections, the longitudinal end portions of said side sections being of such a thickness as to permit the flexing of said end portions in either direction, transversely or longitudinally, at least one of said longitudinal end portions being provided 60 with a sharpened edge, said center portion being of such thickness that it is flexible longitudinally of the blade but is substantially non-flexible transversely of the blade, whereby flexing strain cross-sectionally of the blade is borne substantially entirely by said side sections.

65. 15. As a new article of manufacture, an integral razor blade made of a strip of spring steel and comprising longitudinal flexible side sections and a relatively thicker longitudinal center portion 65 of a heavier gauge than that of the side sections, the longitudinal end portions of said side sections being of such a thickness as to permit the flexing of said end portions in either direction, transversely or longitudinally, at least one of said longitudinal end portions being provided with a sharpened edge, said center portion being of such thickness that it is flexible longitudinally of the blade but is substantially non-flexible transversely of the blade, whereby flexing strain cross-sectionally of the blade is borne substantially entirely by said side sections, said longitudinal center portion being provided with a ridge for guiding the blade in its sliding movement.

70. 16. As a new article of manufacture, an integral razor blade made of a strip of spring steel and comprising longitudinal flexible side sections and a relatively thicker longitudinal center portion of a heavier gauge than that of the side sections, said blade provided with an opening adapted to interfit with a portion of a razor blade holder thus holding said blade in selected position, the longitudinal end portions of said side sections being of such a thickness as to permit the 15 flexing of said end portions in either direction, transversely or longitudinally, said longitudinal end portions provided with sharpened edges, said center portion being of such thickness that it is flexible longitudinally of the blade but is substantially non-flexible transversely of the blade, whereby flexing strain cross-sectionally of the blade is borne substantially entirely by said side sections of the blade.

75. 17. A device forming a razor blade holder comprising in combination a handle and a head including a lower section and at least one upper section, said lower section being provided with a cut out portion and with a plurality of comb portions, said upper section being hingeably secured to said lower section, said lower section being provided with a movable element having at least a portion thereof positioned within said cut-out portion, said movable element being provided with recessed portion shaped in such a 20 manner that said element may cooperate with a blade so as to hold same in selected position and means within said handle for moving said element longitudinally of said handle and adjusting said blade for shaving purposes.

80. 18. A device forming a razor blade holder comprising in combination a handle and a head including a lower section and an upper section hingeably secured to each other, one of said sections provided with a guard portion, said lower section being provided with a cut-out portion and with a movable member having a portion thereof positioned within said cut-out portion, said member being provided with at least one cut-out portion shaped in a manner so that the latter may 25 cooperate with a blade supported by said device, said device provided with means for moving said member longitudinally of said handle and adjusting said blade for shaving purposes.

85. 19. A device forming a razor blade holder comprising a handle and a head provided with means for supporting a blade therein, said head including upper and lower sections, a movable member associated with said head, at least one of said sections provided with at least one comb portion, 30 said lower section provided with a cut-out portion adapted to receive a part of said movable member, the upper section of said member provided with a cut-out portion shaped in a manner so that said section may interfit with a portion of 35

5 a blade holding same against angular displacement, and rotatable means associated with said handle cooperating with a portion of said member for moving same longitudinally of said handle and adjusting said blade for shaving purposes.

10 20. A device forming a razor blade holder comprising a handle and a head including upper and lower sections, at least one side portion of said lower section being provided with a guard portion, said lower section provided with at least one cut-out portion, said head provided with a movable member, a portion of said member

adapted to be seated within said cut-out portion, said member provided with a cut-out portion shaped in such a manner so that the latter may cooperate with a blade holding same against lateral movements, said member being provided with a portion extending within said handle, a rotatable element associated with said handle and adapted to engage said extending portion for the purpose of moving said member longitudinally of said handle and adjusting the blade for shaving 10 purposes. 5

JACOB L. KLEINMAN.
